UNITED STATES PATENT OFFICE.

WILLIAM FRANKLIN BROTHERS, OF BROOKLYN, NEW YORK.

BALANCED CRANE OR DERRICK.

1,245,186.

Specification of Letters Patent.

Patented Nov. 6, 1917.

Application filed March 9, 1914, Serial No. 823,349. Renewed April 12, 1917. Serial No. 161,678.

To all whom it may concern:

Be it known that I, WILLIAM F. BROTHERS, a citizen of the United States, and a resident of the city of Brooklyn, county of 5 Kings, State of New York, have invented new and useful Improvements in Balanced Cranes or Derricks, of which the following is a description.

The object of this invention is the production of a crane or derrick constructed and arranged whereby its parts are in equilibrium or counterbalanced relation, whether the crane or derrick be loaded or unloaded. More particularly my invention is directed 15 to cranes or derricks having a base and operating parts related to said base whereby such operating parts in the positions of raising and lowering or transferring the load are in balanced equilibrium. More specifically 20 my invention in certain particular forms thereof, comprises a support, a counterweight base, said base being pivotally carried by said support, a boom pivotally connected with said counterweight base, and 25 chains or the like passing over the free end of said boom together with means for operating the chains whereby to raise or lower the load. Preferably, such support is mounted to be movable on a fixed or mov- 30 able support, such as the truck or platform of a car, a foundation or the like, and the chain operating means is carried on the base. Preferably, also, the effective distance of 35 the free end of the pivoted boom from the pivotal center of the counterweight base, is arranged to be variable as by means of chains or the like operated by suitable actuating means. By reason of the construction and arrangement of my invention, 40 cranes and derricks embodying my invention are operated without requiring any support or bracing other than that afforded by the platform of the car or the foundation, etc., on which the crane may be carried or 45 placed.

Other features and objects of my invention will be more fully understood from the following description and accompanying drawings in which—

50 Figure 1 is a side elevation of one form of a crane embodying my invention suitable as a locomotive crane;

Fig. 2 is a side view of the crane shown in Fig. 1 in the position of raising a load;

55 Fig. 3 is a plan view of the same;

Figs. 4, 5 and 6 are side elevations of modifications.

Referring to Figs. 1, 2 and 3, the support 1 of the crane is shown mounted on a central step 2 and rollers 3, 3 to be rotatable 60 on the platform 4, of a railway car or truck. The standards 5, 6 are fixed at their lower ends to the movable support 1, and carry the shaft 7 at their upper ends. The counterweight base 8 is hung by arms 9, 10 from 65 the shaft 7. As shown, the arms 9, 10 are pivoted at opposite pivots 11, 12 to counterweight base 8 proximate the central line thereof. The counterweight base 8 is designedly weighted to a predetermined 70 weight, or constructed to have any desired variable weight up to a predetermined maximum, dependent upon the maximum load and other conditions as will more fully appear hereinafter. As also shown and as 75 more fully described hereinafter, the weight of the counterweight base 8 may include the operating drum or drums, the actuating motor or motors, and the source of power such as a boiler if the same be desired to be used, 80 and such other auxiliary means as may be employed, and the counterweight base is arranged to provide for sufficient space for carrying the said parts.

The boom 13 is shown pivoted to counterweight base 8 at the opposite pivots 11, 12 along the central line of said base 8; such construction of common pivotal means for the counterweight suspension means and the boom pivotal means affords simplified construction, though of course, said two pivotal means may be separate. The boom 13 is shown as of a general V-shaped frame comprising outer members 14, 15, with transverse brace members 16, and latticed cross 95 members 17.

The distance of the free end of the boom 13 from the pivots of arms 9, 10, may be controlled, as shown, by the chains or rope 18 operated by suitable controlling mechanism. 100 In these figures I have indicated the chain or rope 18 secured at one end to the "dead" eye 19 carried by shaft 7, said chain or rope 18 extending over the sheave 20 carried by shaft 21 disposed at the free end of the boom 13, and passing thence over the sheave 22 on shaft 7 and thence wound about the operating drum 23. I have indicated an electric motor 24 geared by suitable gearing with the operating drum 23 and controlled 105 110

with respect to speed and direction of rotation by the control lever 25 and suitable regulating apparatus. By operating the drum 23 to wind thereon the chain or rope 18, the effective distance between the free end of boom 13 and the pivots of arms 9, 10, will be shortened; likewise, when the chain or rope 18 is unwound from the drum 23, the effective distance of the free end of boom 13 from the pivots of arms 9, 10 will be increased.

I have shown the hoisting chain or rope 26 controlled by the drum 27 shown also operated by the motor 24 geared thereto by suitable gearing and regulating arrangement for deriving variable rotation in speed and in direction. As indicated, one end of the hoisting chain or rope 26 may be secured to the drum 27, the chain or rope 26 thence passing over the sheave 29 carried by shaft 21 disposed at the free end of boom 13, over sheave 30 of block 31, thence passing over the sheave 32 carried by shaft 21 and finally having its other end secured to the "dead" eye 33 on block 31. The block 31 is shown provided with the hook 34 to facilitate attachment thereto of the load. By mounting the sheaves 29 and 32 carrying the hoisting chain or rope 26 on shaft 21 and on opposite sides of the sheave 20, carrying the chain or rope 18, also mounted on shaft 21, the thrust of the load borne by the load chain or rope 26 will be balanced with respect to the boom or frame 13, and stresses tending to twist or distort the boom or frame 13 will be precluded.

I have shown the support 1 as provided with a circumferential rack 35 coöperating with the gear 36 driven by the motor 37 whereby the circular support 1 may be turned in either direction by suitably controlling the motor 37. It will be understood that the same motor may be employed for turning the movable support 1 as well as for operating the drum 23 and the drum 27; also, if desired, it will be clear that separate motors may be employed for separately driving the drum 23 and the drum 27.

The operation of the crane shown in Figs. 1, 2 and 3 will be understood from the description hereinbefore set forth taken in connection with the following. After suitably operating the drum 23 to secure the positioning of the boom 13 with respect to the load to be raised, the block 31 is then lowered by letting out the hoisting chain or rope 26 and the load is then secured to the hook 34. As soon as any appreciable strain is exerted in the hoisting chain or rope 26 upon operating the drum 27 to wind thereon the chain or rope 26, such strain will tend to move the counterweight base from the vertical plane away from the load, as is indicated in Fig. 2. Upon further increase in tension in the hoisting chain or

rope 26, the counterweight base 8 will move farther and farther from the vertical until the load has been raised and is wholly carried by the hoisting chain or rope 26. During such movement of the crane, the operating parts will be at all times in counterbalanced position whereby there is no tendency of support 1 or the standards 5, 6, carried thereby to be tilted or otherwise displaced from the vertical. Such relationship of the coöperating parts of my invention obviates the necessity of guy ropes or other lateral supporting or bracing means. The degree to which the counterweight is moved from the vertical when the load is wholly carried by the hoisting chain or rope, will be dependent on the weight of the load, the weight of the counterweight and the effective distance of the sheave of the boom from the pivot of the counterweight. 85

In the specific crane illustrated in Figs. 1, 2 and 3, I have shown the counterweight or counterweight base to be suspended by being pivoted in a plane passing through its center of gravity, and the drum, motor and such other operating devices disposed on the counterweight base so that the counterweight base remains substantially horizontal. This condition will still obtain notwithstanding movement of the operator over the counterweight base or the varying weights of different operators, who may operate the crane, since the combined weight of such devices and the counterweight base itself will ordinarily be ample to prevent any material deviation of the counterweight base from the horizontal plane. 100

Such construction is preferable when it is desired to install a boiler on the counterweight base, in which case it is desirable 105 to maintain horizontal condition of the counterweight base. In such cases where the crane is made portable or otherwise capable of being bodily transported, it is desirable to lock the counterweight 8 to prevent the same from being set in vibration. Such tendency toward vibration will be prevented by "reefing in" the boom 13 until the boom 13 comes into contact with the shaft 7; or, if desired, a suitable locking means such as 115 the latch comprising the hook 38 carried by the standard 5 and latch bar 37 carried by the counterweight 8 may be employed.

In Fig. 4 I have shown the counterweight or counterweight base 8 to be suspended from oppositely disposed cables 40, 40 respectively, passing about the grooved rollers 41, 41, carried by shaft 7 and about grooved rollers 42, 42, pivoted or otherwise secured to the counterweight or counterweight base 125 8. Under certain circumstances, the counterweight base may be suspended by arms rigidly secured thereto, in which case the counterweight base will depart from the horizontal plane when deflected laterally by 130

the load. Such construction is indicated in Fig. 5, wherein the counterweight is suspended by means of the frame 45 which is fixed at its lower end to counterweight base 8 and pivoted at its upper end to shaft 7. In Fig. 5, the boom 13 is indicated as pivoted to the counterweight 8 at points without the central line thereof, or out of the plane passing through the center of gravity 10 of the counterweight. However, the boom may be pivoted on the central line and in the plane of the center of gravity of the counterweight when the counterweight is hung from suspension arms which are rigidly connected to the counterweight.

It will be understood that the counterweight may be varied in weight by forming the counterweight of a body or frame to which may be added additional weighting parts to increase the counterweight effect; such parts may be taken off to lessen the counterweight effect to any desired amount. The types of crane shown in the drawings are adapted to be thus varied in counterweight effect; thus, in the form of my invention shown in Fig. 4, the length of the suspension cables 40, 40, may be varied in accordance with the mass of the counterweight. The counterweight may also be built in the form of a tank the interior of which may be filled more or less with a weighting substance such as water, sand, etc.

In Fig. 6 I have shown another form of my invention comprising a support 50 of concave or saucer-shaped construction mounted on a railway car by means of the central step 51, and adapted to be rotated by means of the circular rack 52. The counterweight 53 is supported by the support 50, preferably by the use of bearing rollers 54. The boom 55 is pivoted to the counterweight 53, the free end of the boom 55 being controlled by the chain or rope 56, having one end secured to the "dead" eye 57, and the other end wound on the operating drum 58. The chain or rope 59 for raising and lowering the load passes from the operating drum over the sheave 60, thence through the block 61 and finally to the "dead" eye 62. The counterweight 53 is shown to be variable in weight by adding or taking off one or more of the weighting parts 63. In this construction, my invention is carried out without the use of standards or other pivotal suspension means for the counterweight.

When transporting the crane or derrick constructed in accordance with my invention, the vehicle or platform of the car on which the crane is mounted, may be made of sufficient length to allow the boom to be lowered on the same, and thus prevent the counterweight from being set in vibration which may arise while being bodily transported.

65 In addition to the advantages set forth

above, my crane does not require skilled labor to operate the same, since the counterbalancing relation of the parts thereof precludes possibility of overturning or wrecking the crane even in the hands of an inexperienced operator.

70 It will be understood that many changes and modifications in the specific apparatus described herein may be made without departing from my invention.

75 What I claim and desire to secure by Letters Patent is:

1. In a crane or the like, the combination of a support, a standard in fixed relation thereto and carried thereby, a counterweight pivoted to said standard, and a boom pivoted to said counterweight.

80 2. In a crane or the like, the combination of a support, a standard in fixed relation thereto and carried thereby, pivotal means carried by said standard, a counterweight base pivoted to said pivotal means and a boom pivotally connected with said counterweight base.

85 3. In a crane or the like, the combination of a support, standards carried thereby and in fixed relation thereto, a shaft carried by said standards, a counterweight base pivoted to said shaft and a boom pivotally connected with said counterweight base.

90 4. In a crane or the like, the combination of a support, a standard carried thereby, a counterweight hung from the standard, a boom pivotally connected with said counterweight and means for controlling the relation of the free end of said boom to the point of suspension of said counterweight.

95 5. In a crane or the like, the combination comprising a support, a standard carried thereby, a counterweight hung from the standard, a boom pivotally connected with said counterweight and means for adjustably controlling the distance of said boom from the pivot of said counterweight.

100 6. In a crane or the like, the combination comprising a support, a standard carried thereby, a counterweight pivotally supported from the standard, means for varying the effective counter-balance produced by said counterweight, a boom pivotally connected with said counterweight, and means carried by said boom for raising and lowering the load.

115 7. In a crane or the like, the combination of a support, a standard carried thereby, a counterweight pivotally supported from the standard, said counterweight being constructed of two parts of variable weight to vary the effective counter-balance produced by said counterweight, a boom pivotally connected with said counterweight, and means carried by said boom for raising and lowering the load.

120 8. In a crane or the like, the combination of a support, a standard carried thereby, a

counterweight pivotally supported from the standard, means for varying the counterbalance effect produced by said counterweight, a boom pivotally connected at one end with said counterweight, means for varying the distance of the other end of said boom from the pivots of said counterweight, and means carried by said boom for raising and lowering the load.

10. 9. In a crane or the like, the combination of a support, standards mounted on said support, a shaft carried by said standards, a counterweight, means for yieldingly mounting said counterweight on said shaft, a boom, means for yieldingly connecting one end of said boom to said counterweight, means for yieldingly connecting the other end of said boom with said shaft, and means for raising and lowering the load.
15. 10. In a crane or the like, the combination of a support, standards mounted on said support, a shaft carried by said standards, a

counterweight base, means for suspending said counterweight base from said shaft, said suspension means maintaining said counterweight base substantially horizontal, a boom yieldingly connected to said counterweight base, and means for raising and lowering the load.

11. The combination of a support, a counterweight, a boom yieldingly connected with said counterweight, means coöperating with said boom for raising and lowering the load and means carried by the support permitting the counterweight and boom to be oscillated relative to the support.

In testimony whereof I have signed this specification in the presence of two subscribing witnesses.

WILLIAM FRANKLIN BROTHERS.
